(57) **CLAIM**

The ornamental design for a self-watering planter, as shown and described.

DESCRIPTION

FIG. 1 is a perspective view of self-watering planter;

FIG. 2 is a top plan view thereof;

FIG. 3 is a bottom plan view thereof;

FIG. 4 is a front elevation view thereof;

FIG. 5 is a back elevation view thereof;

FIG. 6 is a side view thereof; and,

FIG. 7 is opposite side view thereof.

The broken lines depict environmental subject matter only and form no part of the claimed design.
